(57) **CLAIM**

The ornamental design for a sealing membrane as shown and described.

DESCRIPTION

FIG. 1 is a perspective view of a sealing membrane embodying the invention.

FIG. 2 is a left side view of the sealing membrane of FIG. 1. The right side of the sealing membrane is a mirror image of the left side.

FIG. 3 is a top view of the sealing membrane of FIG. 1. The bottom is a mirror image of the top.

FIG. 4 is a cross sectional view of the sealing membrane of FIG. 1; and,

FIG. 5 is another cross-sectional view of the sealing membrane of FIG. 1.

The elements shown in broken lines are included for the purpose of illustrating environment and form no part of the claimed design.
